ATTORNEY

UNITED STATES PATENT OFFICE

153,803

DESIGN FOR AN ELECTRICAL PUSH- BUTTON COVER PLATE

William Huppert, New York, N. Y.

Application October 30, 1946, Serial No. 134,391

Term of patent 14 years

(Cl. D26—13)

To all whom it may concern:

Be it known that I, William Huppert, a citizen of the United States and a resident of the city, county, and State of New York, have invented a new, original, and ornamental Design for an Electrical Push Button Cover Plate, of which the following is a specification, reference being had to the accompanying drawings, forming part thereof, in which—

Figure 1 is a front view of an electrical push button cover plate, showing my new design;

Fig. 2 is a side view thereof; and

Fig. 3 is a vertical section taken on the line 3—3 of Fig. 1.

The dotted lines in Fig. 3 are shown for illus-

trative purposes only to indicate a push button in association with the cover plate.

I claim:

The ornamental design for an electrical push-button cover plate, substantially as shown and described.

WILLIAM HUPPERT.
